DESIGN FOR A MECHANICAL PENCIL

Sylvester G. Lipic, Sappington, Mo.

Application May 12, 1947, Serial No. 138,990

Term of patent 14 years

(Cl. D74—24)

To all whom it may concern:

Be it known that I, Sylvester G. Lipic, a citizen of the United States, residing at Sappington, county of St. Louis, State of Missouri, have invented a new, original, and ornamental Design for a Mechanical Pencil, of which the following is a specification, reference being had to the accompanying drawing, forming part thereof.

Fig. 1 is an elevational view of a mechanical pencil, embodying my new design;

Fig. 2 is a view similar to Fig. 1, along a plane 90° removed from that shown in Fig. 1; and

Fig. 3 is a top view.

I claim:

The ornamental design for a mechanical pencil, as shown.

SYLVESTER G. LIPIC.
